S. H. KLEEBERG,
FOUNTAIN SHAVING BRUSH,
APPLICATION FILED MAR. 18, 1916.

1,194,642.

Patented Aug. 15, 1916.

Inventor

Sydney H. Kleeberg,

By William E. Baff.

Attorney

UNITED STATES PATENT OFFICE.

SYDNEY HERBERT KLEEBERG, OF NEW YORK, N. Y.

FOUNTAIN SHAVING-BRUSH.

1,194,642.

Specification of Letters Patent. Patented Aug. 15, 1916.

Application filed March 18, 1916. Serial No. 85,042.

To all whom it may concern:

Be it known that I, SYDNEY H. KLEEBERG, a citizen of the United States, residing at the city of New York, State of New York, 5 have invented certain new and useful Improvements in Fountain Shaving-Brushes, of which the following is a specification.

This invention relates to improvements in brushes and more particularly to fountain shaving brushes,—a type of shaving brushes provided with means for dispensing soap in liquid form so that the soap may be fed by manually-operated means.

One of the objects of my invention is to 15 provide a sanitary shaving brush carrying its own supply of liquid shaving soap and equipped with simple, inexpensive, and highly efficient mechanism for feeding any desired amount of liquid soap to the bristles 20 of a brush.

A further object of my invention is to reduce the number of parts in a device of the kind described. To this end, I provide a discharge spout at one end of a hollow 25 handle for dispensing soap, a valve controlling the flow of soap through this spout, and, at the opposite end of said handle I provide an actuating push-button for the proper operation of the valve.

Another object of my invention is to provide, in a device of the kind described, a soap-dispensing handle provided with a filler opening at one end, a soap feeding mechanism at another end, and with a closure 35 for the filler opening which assists, at the same time, to operate said soap-feeding mechanism.

A still further object of my mechanism is to provide, in a device of the character described, a soap-dispensing handle having a filler opening at one end and a transparent closure for said opening so as to make said filler opening also a sight opening, said closure being removable to give access to the 45 interior of said handle and also providing a push button as a means of controlling a valve carried by the handle at the brush end thereof, so as to cheapen the cost of manufacturing a fountain shaving brush.

Another object of my invention is to provide a cup removably secured to a hollow handle at one end so as to close the same

and also providing a means for anchoring the bristles of the brush and for feeding soap thereinto.

55

With the above and further objects in view my invention consists in the combination, arrangement, and details of construction disclosed in the drawings and specification and then more particularly pointed out 60 in the appended claims.

In the drawings wherein similar reference characters designate similar parts throughout the respective views, Figure 1 is a longitudinal sectional view of my invention, Fig. 65 2 is a rear end elevation thereof. Fig. 3 is a front view of the cup with the brush removed, and Fig. 4 is a cross-section taken on line 4—4 of Fig. 1.

Referring to the drawings which are 70 merely illustrative of my invention there is shown a handle-shaped sleeve 1 formed at one end with an offset or turned edge 2 which is provided with a threaded filler opening 3 through which shaving soap in 75 preferably liquid form is introduced to fill the barrel of the sleeve. This handle or sleeve 1 is made of any suitable material such as sheet metal and has a bracket 4 formed integrally thereupon in a plane 80 with said filler opening, this bracket being of any approved form so as to provide a portion arranged to project radially of said handle; I prefer to enlarge the threaded edge of said opening so as to provide a collar 85 threaded for the reception of a push-button holder in the form of a ring or annular member 5. The bracket extends as a part of this collar, and said ring has external screw threads by means of which it may be 90 screwed into the threaded filler collar 6 and be supported thereby. The bracket 4 includes a preferably rightangular portion or bearing 7 extending transversely in said handle against which portion 7 bears one 95 end of a spring 8 coiled around a valve rod 9' passing through a guide opening in said portion 7 so as to be guided in movement thereby. The opposite end of the spring 8 bears against a head 9 screwed on one end 100 of rod 9' so as to cause the conical valve 11' formed at one end of the rod 9' to firmly engage the correspondingly shaped valve seat 11' formed upon a tubular projection or

spout 12 serving as a feeder of soap from the handle to the brush 13.

The spout 12 is connected to the hollow handle concentrically thereof in a manner to permit the inner part of the bristles of the brush to be anchored against the extension forming a part of the brush head. I prefer to form a metallic cup 14 as a separate piece, the spout 12 being formed integrally and concentrically of this cup, so that the bottom of the cup may close the sleeve or handle at one end when the cup is fitted into the sleeve and secured thereto, in a removable fashion by any suitable means such as screws 14' tapped into sleeve and cup and projecting into the bristles of the brush. It will be thus seen that the cup 14 can be removed thus permitting the brush to be renewed at will, without disturbing the actuating parts of the device, as the head 9 is screw-threaded upon the rod 9' so as to be removable therefrom.

The push-button holder or ring 5 has a flush inner circumference in which slides the preferably circular or annular push-button 16 formed of transparent material and forming a means for actuating the valve to open the valve port or seat 11. This push button 16 is fitted with a peripheral packing ring 17 as well as an air compressor, as the button acts in the nature of a piston, the packing serving to provide a fluid-tight connection between the button 16 and ring 5 as said button slides in the latter and thus prevents leakage of soap. The ring 5 is formed with an internal flange 18 at right angles to its axis near one end which preferably has a milled edge 19 and it serves not only as a stop to limit the extent of threaded movement of the ring 5 in an inward direction in the opening 3 and collar 6, but also as a finger hold for turning the ring and tightening or removing it. At one end, in advance of the external flange is an internal flange 20 forming a stop for the push-button 16, the spring 8 not only holding valve 11' closed but causes the head 9 to bear against the push-button 16 holding the latter against flange 20, the spring being stiff and not under tension. Instead of the flange 20 a number of stops may be provided (not shown) and another internal flange 20 or stop, as the case may be, is formed as at the opposite end of the ring or holder 5 which also limits the play of the push-button 16. The push-button 16 being transparently convenient sight opening is provided for blewing the contents of the handle. It will now be seen that by depressing the push-button 16 the head 9 will be acted upon to push the rod 9 against the tension of spring 8 thereby compressing air in the barrel 1 unseating valve 11' and forcing soap through the port 11 to the bristles of the brush 13 or other soap applier. When pressure is removed from

the push-button the spring 8 rebounds thereby closing valve 11' and restoring push-button 16 to its normal inactive position. It will be observed that as the flange 18 projects in advance of the handle the push-button will also project outside the handle thereby making it easier to get at the push-button to operate it.

From the foregoing explanation it will be seen that a simple, inexpensive and easily operated shaving brush is provided. By turning the milled flange 18 the ring 5 with the push-button in it can be removed, being unscrewed from the opening 3, without causing the valve to be opened, and permitting the handle to be filled with soap.

Numerous modifications may be resorted to in practice without departing in principle from the subject-matter covered by the appended claims.

What I claim and wish to protect is the following:—

1. A fountain shaving brush consisting of a hollow handle, a brush secured at one end of said handle, a tubular feeder disposed concentrically of said hollow handle and projecting into said brush, said feeder having a port, a valve, a filler ring integrally formed upon said handle, a bracket carried by said ring, a rod guided in said bracket and secured at one end to said valve, a spring bearing at one end against said bracket a push-button in said filler ring, a head screwed on said rod against which the opposite end of said spring bears, said push button adapted to depress said rod and valve, and means for holding said push-button against displacement.

2. A device as described consisting of a hollow handle, said handle being provided at one end with a brush head, a concentric spout, formed integrally upon said brush head and having a port, a brush secured at its inner end against said sleeve and around said spout, said handle being formed at its opposite end with a threaded opening, a transparent push-button arranged to close said opening, a tubular guide for said button being of a uniform diameter and threaded in said opening so as to project into said handle, a valve engaging the outer edge of said spout to close said port, and means controlled by said push button for causing said valve to open and close said port.

3. A device of the kind described consisting of a hollow handle, said handle being formed with an opening at one end, a brush, a brush head for said brush removably secured to the other end of said handle, a guide member having a tubular part threaded into said opening, a push-button slidable between the ends of said guide member, a central tube formed upon said brush head, said central tube being formed with a port, a valve arranged to close said port,

and means controlled by said push-button and adapted to operate said valve.

4. A device of the kind described consisting of a hollow handle formed with a threaded opening at one end, an inwardly projecting bracket formed on said handle, a ring threaded into said opening, an outer flange on said ring and engaging said handle to hold said ring in position, a slideable push-button in said ring, limiting stops at the opposite ends of said ring between which said push button moves, a feeder fitting in said handle and having a valve seat, a valve adapted to engage said seat, a rod secured at one end to said valve, said rod passing through said bracket and bearing against said push-button, a spring coiled around said rod and bearing at one end against said bracket and adapted to cause said button to engage one of said stops to cause said valve to engage said seat.

5. In a device as described the combination of a hollow handle, said handle being formed with a threaded opening and with a bracket projecting in advance of said opening, a valve-operating rod operating in said bracket, a ring threaded into said threaded opening, an external flange formed on said ring and engaging said handle and forming means for unscrewing said ring, a piston sliding in said ring and having a peripheral packing engaging the inner wall of said ring and serving as the only closure for said opening, a head on said rod bearing against said piston, and a spring surrounding said rod and engaging said bracket at one end and said head at its opposite end.

6. In a device of the kind described, in combination a brush, a hollow handle, means for securing said brush in said handle, said handle being formed with a threaded opening, a ring threaded into said opening, an internal flange formed at one end of said ring, an external flange formed in advance of said internal flange and having a milled edge, said flange engaging said handle so as to space said internal flange from the latter, a push-button mounted for slideable movement in said ring, a spring holding said button against said internal flange, and

a bearing carried by said ring against which said spring bears.

7. A fountain shaving brush comprising a hollow handle, a brush head secured at one end thereof and engaging said brush, said brush head being provided with a spout projecting into said brush, a valve controlling said spout, said handle, at its opposite end being formed with a transverse flange provided with an inwardly-projecting internally-threaded annular portion of a uniform diameter, a ring threaded into said annular portion, a piston snugly and slidably fitting said annular portion, resilient means engaged by said piston to unseat said valve, and a stop carried by said ring for holding said piston against displacement.

8. A fountain shaving brush comprising a hollow handle, an annular portion projecting internally of said handle from one end thereof, said annular portion forming a filler opening, opposing flanges formed upon said portion, a piston snugly fitting said annular portion and sliding between said flanges, a spring adapted to hold said piston against one of said flanges, said piston arranged to close said filler opening, when sliding and at rest, a brush, a liquid feeder associated with said brush, and means controlled by said piston adapted to control said feeder.

9. A fountain shaving brush comprising a hollow handle, a brush secured to said handle at one end, a cylindrical member being open at each end, a transparent piston snugly fitting said cylindrical member, and a right angular flange formed upon said cylindrical member, said handle being internally threaded at one end, said cylindrical member being threaded into said handle at one end and adapted to have said flange engaging said handle to limit the threaded movement of said member.

In testimony whereof I have affixed my signature in presence of two witnesses.

SYDNEY HERBERT KLEEBERG.
